DESIGN FOR A DISPLAY CARD OR SIMILAR ARTICLE

Gilbert J. Rhodes, New York, N. Y.

Application December 2, 1939, Serial No. 88,627

Term of patent 3½ years

To all whom it may concern:

Be it known that I, Gilbert J. Rhodes, a citizen of the United States of America, residing in the city of New York, county of New York and State of New York, have invented a new, original, and ornamental Design for a Display Card or Similar Article, of which the following is a specification, reference being had to the accompanying drawing, forming part thereof.

The figure in the drawing is a top plan view of a display card or similar article, showing my new design.

The display card is flat and has no substantial thickness.

I claim:

The ornamental design for a display card or similar article, substantially as shown and described.

GILBERT J. RHODES.
